United States Patent Office

Des. 182,103
Patented Feb. 18, 1958

182,103

PHONOGRAPH CABINET

Melvin H. Boldt, Glenview, Ill., assignor to AMI Incorporated, Grand Rapids, Mich., a corporation of Delaware

Application May 1, 1957, Serial No. 45,960

Term of patent 14 years

(Cl. D56—4)

Fig. 1.

I claim:

The ornamental design for a phonograph cabinet, as shown.
